Patented June 26, 1928.

UNITED STATES PATENT OFFICE.

CARL O. PETERSON, OF LYNN, MASSACHUSETTS.

PORTABLE SUN AND WIND SHIELDING DEVICE.

Application filed July 8, 1927. Serial No. 204,351.

The object of the invention is to provide a canopy or tent-like structure for beach resorts and the like which can readily be assembled and disassembled and easily transported in a compact manner in an automobile or other convenient way.

The detailed structure and advantages of my invention will be more clearly illustrated and described in the accompanying specification and drawing in which Fig. 1 represents in perspective a complete assembly in situ of the sun and windshield device of my invention; Fig. 2 in partial side elevation and partial section the method of attaching the top covering or awning to one of the rods or posts which are embedded in the sand; Fig. 3 represents a similar view in elevation; Fig. 4 represents one of the supporting rods or sheaves for closing the supporting rods or posts together with a guy-rope attached thereto; Fig. 5 represents the conventional guy-rope tightener such as is used in ordinary tent structures, and Fig. 6 represents one of the sheaves with guy-rope attached, both in side elevation.

Referring more particularly to Fig. 1, 1 represents the supporting posts or rods to which the awning or covering 2 is attached or on which it is supported. These rods or on which it is supported. These rods 30 may be made of any suitable material such as steel rod of suitable diameter, and preferably are provided with hooks or loops 3 at their top end over which hooks is slipped the awning or covering by turning the reenforced holes 4 in the latter over the ends 5 of the hooks until the awning 2 occupies a horizontal position or at least a right angle plane with reference to the length of the rods 1. In order to prevent the awning 2 from slipping over the part of the hook or loop 3 at 6 and down over the straight part of the rod to the sand or ground, a sheave 7 is provided for closing the hook or loop 3 at 5 and for supporting the awning 2 so that the latter may not slip down the rod as above described. This sheave has an additional function, viz., that of carrying the guy-rope 8 which is attached at its lower end to the bars 9, the latter being buried in the sand or ground at a suitable angle to render it the most difficult to pull these bars out of the sand by either a gust or steady wind. By burying the rods 1 and the bars 9 sufficiently well in the sand it will be found that the construction affords a very stable resistance for all practicable purposes to ordinary

prevailing winds at a beach resort and the like. The sheave construction for preventing slipping down of the covering or awning as well as its guy-rope supporting function 60 is an especially novel and useful one.

The windshield 11 is provided with rods similar to the rods 1 of the sun-shield, and also provided with sheaves, guy-ropes and anchor bars in a similar manner. The rods, however, in the case of the windshield are inserted through loops or envelopes in the fabric at 12, 13 and 14. The windshield may be high enough only to act to break the wind or it may extend the full height of the sun-shield if desired. As a shelter against storm, additional sides of similar character may be raised.

One quick method of erecting the sun-shield is to spread the canvas, awning or suitable covering on the sand and insert through the holes therein the rods 1, embedding the latter in the sand; then raising the awning up the rods, and subsequently inserting the sheaves in the loops of the rods 70 at right angles thereto, as shown in Fig. 4, and subsequently turning the sheave back into place as illustrated in Figs. 2 and 3. When the guy-ropes connected with the sheaves are now fastened to the anchor-bars 80 9 the sheaves will be retained in place and the whole structure will be rigid enough for practical purposes, although the total time consumed in the erection thereof has only 90 consumed a few minutes. When it is desired to take down the sun and wind-shield or disassemble it, it only takes a few moments also by reversing the process of assembly.

What I claim as new and desire to secure by Letters Patent of the United States is:

1. In a portable sun and wind shielding device the combination of a plurality of hooked rods for insertion in the ground, an awning or covering detachably supported by said rods, a sheave insertable in the hook of each rod for the purpose of preventing the covering from sliding down the rod, and a plurality of ropes one attached to each sheave at one end and anchored to the ground at the other for reinforcing the shielding device provided by the assembly of the structural parts hereinbefore mentioned.

2. In a portable sun and wind shielding device the combination of a fabric roof

covering, eyelets therein, a plurality of rods for insertion in the ground to support the covering, hooks on the rods for receiving the eyelets in the covering, a sheave supported in each hook of the rods for the purpose of preventing the covering from sliding down the rods, and suitable guy-ropes attached to the respective sheaves at one end and anchored to the ground at the other for rigidly maintaining the rods and covering in place.

3. In a portable sun and wind shielding device for beach resorts, the combination of

a supporting rod for insertion in the sand, a hook at the top of said rod, a covering 15 fabric suitably eyeletted for slipping over the hook end of the rod, a closure device such as a sheave for closing the opening in the covering, a suitable anchor bar also for insertion in the ground, and a guy-rope one end of which is attached to the sheave or closure and the other end of which is attached to the anchor bar.

CARL O. PETERSON.
